CLAIM

We claim the ornamental design for a foldable mobile phone with transitional graphical user interface, as shown and described.

DESCRIPTION

FIG. 1 is a front view of the first image in a sequence of a first embodiment of a foldable mobile phone with transitional graphical user interface showing our new design, with the transitional graphical user interface displayed on an outer display screen of the mobile phone in a folded state; FIG. 2 is a rear view thereof;

FIG. 3 is a front view of the second image thereof, with the transitional graphical user interface displayed on an outer display screen of the mobile phone in a folded state; FIG. 4 is a rear view thereof;

FIG. 5 is a front view of the third image thereof, with the transitional graphical user interface displayed on an inner display screen of the mobile phone in an open state;

FIG. 6 is a rear view thereof;

FIG. 7 is an enlarged view of the portion 7 encircled in FIG. 1;

FIG. 8 is an enlarged view of the portion 8 encircled in FIG. 3;

(Continued)

FIG. 9 is an enlarged view of the portion 9 encircled in FIG. 5;

FIG. 10 is a front view of the first image in a sequence of a second embodiment of a foldable mobile phone with transitional graphical user interface showing our new design, with the transitional graphical user interface displayed on an outer display screen of the mobile phone in a folded state; FIG. 11 is a rear view thereof;

FIG. 12 is a front view of the second image thereof, with the transitional graphical user interface displayed on an outer display screen of the mobile phone in a folded state; FIG. 13 is a rear view thereof;

FIG. 14 is a front view of the third image thereof, with the transitional graphical user interface displayed on an inner display screen of the mobile phone in an open state; FIG. 15 is a rear view thereof;

FIG. 16 is an enlarged view of the portion 16 encircled in FIG. 10;

FIG. 17 is an enlarged view of the portion 17 encircled in FIG. 12; and,

FIG. 18 is an enlarged view of the portion 18 encircled in FIG. 14.

The evenly-spaced broken lines in the figures depict portions of the foldable mobile phone with transitional graphical user interface which form no part of the claimed design.

The dot-dash broken lines in the figures encircling portions of the claimed design that are illustrated in enlargements form no part of the claimed design.

The appearance of the transitional graphical user interface sequentially transitions between the images shown in FIGS. 1, 3 and 5; and FIGS. 10, 12 and 14, respectively. The process or period in which one image transitions to another forms no part of the claimed design.

The grayscale tones in the drawings indicate a contrast in appearance.

1 Claim, 18 Drawing Sheets
